UNITED STATES PATENT OFFICE.

CHARLES BARNS, OF SYRACUSE, NEW YORK.

METHOD OF CONNECTING NECK-BANDS, YOKES, AND CUFFS TO SHIRTS.

SPECIFICATION forming part of Letters Patent No. 229,232, dated June 29, 1880.

Application filed March 4, 1880. (No model.)

To all whom it may concern:

Be it known that I, CHARLES BARNS, of Syracuse, in the county of Onondaga, in the State of New York, have invented new and 5 useful Improvements in Connecting Neck-Bands, Yokes, and Cuffs to Shirts, (not patented to me nor, with my knowledge or consent, in any foreign country,) of which the following, taken in connection with the accompanying drawings, is a full, clear, and exact description.

This invention has reference to the connection of the ends of the neck-band, yoke, and cuffs to the body and sleeves of a shirt at the 15 usual slits or openings in same.

Such connections have heretofore consisted in a straight continuation of the connecting-seams of the aforesaid parts and terminating the same at the usual slits or openings in the 20 shirt at or nearly at right angles therewith. This abrupt termination of the seam subjected the fabric to excessive strain at that point, and frequently caused disruption of said parts.

It is to obviate these defects what my invention has for its object; and to this end it consists, essentially, in terminating the connecting-seam of the aforesaid parts with a curve or deflection, so as to intersect the usual slits or openings with an obtuse angle on the 25 edges of the body and sleeves of the shirt to which said parts are joined, substantially as hereinafter more fully described.

In the accompanying drawings, Figure 1 shows my invention as applied to the neck-band and yoke, and Fig. 2 the same as applied to the cuff, of a shirt.

Similar letters of reference indicate corresponding parts.

A represents the neck-band, B the yoke, 35 and C the cuff, of a shirt. The common form

of these members and their connections with the shirt is indicated by the dotted line *xx*, terminating at the usual slit S abruptly, and nearly or quite at right angles therewith, as before described.

The curved full line *a* represents my improved method of joining the neck-band, yoke, and cuffs to the shirt, the said parts being either extended to and sewed to the shirt along that line or having an extra corner-piece, *b*, of the shape of said extension attached to them. The fabric of the shirt in both cases is, as formerly, extended to the dotted line *xx*, thereby producing a double thickness of material in the corner *b*, and thus 45 50 55 re-enforcing the same.

The oblique termination of the seam *a* forms an obtuse angle on the joining edges of the shirt, and by that means obviates the liability 60 of disrupting the parts.

Having thus described my invention, what I claim as new, and desire to secure by Letters Patent, is—

The within-described method of re-enforcing the neck-band, yoke, and cuff connections of a shirt by means of the triangular extension *b*, overlapping the corners of the body and sleeves of the shirt, and having along the ends of the overlapped part thereof the extra seam *xx*, substantially as described 65 70 75 and shown.

In testimony whereof I have hereunto signed my name and affixed my seal, in the presence of two attesting witnesses, at Syracuse, in the county of Onondaga and State of New York, 75 this 28th day of February, 1880.

CHARLES BARNS. [L. S.]
